UNITED STATES PATENT OFFICE.

WILLY PFEFFERKORN, OF ZUG, SWITZERLAND.

DEVICE FOR SEVERING THE HIDES AND SKINS FROM THE KILLED ANIMALS.

1,192,451.

Specification of Letters Patent. Patented July 25, 1916.

Application filed April 5, 1915. Serial No. 19,343.

To all whom it may concern:

Be it known that I, WILLY PFEFFERKORN, electrical engineer, citizen of the Swiss Confederation, residing at Zug, Switzerland, 5 have invented certain new and useful Improvements in Devices for Severing the Hides and Skins from the Killed Animals, of which the following is a specification.

The present invention relates to a device 10 for severing the hides and skins from the killed animals.

The object of the present invention is to provide a device which may be handled by any person and which will not injure the 15 hide or skin even when handled by careless and inexperienced persons.

A further object of the invention is to provide a device which is simple in construction and which allows an expeditious 20 work.

I attain these and other objects by means of the device illustrated in the drawings and described hereinafter.

In the accompanying drawings: Figure 25 1 is a side view parts being in section, Fig. 2 is a front view, Fig. 3 shows part of the device on a larger scale.

Referring to the drawings, 1 designates a frame having a handle 2 and two shields 3, 4. Between the shields 3, 4 there is a disk 5 fixed to a spindle 6. The spindle 6 is rotatably mounted in a bearing 7 of frame 1 and is provided with a bevel gear 9. The bevel gear 9 which is keyed to the shaft 6 35 meshes with a bevel gear 10 fixed to shaft 11. The shaft 11 is rotatably mounted in a bore 12 of the handle 2 and is fastened to the one end of a flexible shaft 13 the other end of which is connected with the shaft of 40 a motor not shown in the drawing. The gears 9, 10 are covered by a casing which consists of two parts 14, 15 screwed on to the shield 3. The disk 5 is provided with three wings 16, the free ends of which are

protruded over parts of the outer edges 18 45 of the shields 3, 4. The free ends of the wings 16 are each provided with incisions 19, 20 formed and arranged in such a manner that three edges 21, 22, 23 of semi-circular shape are formed. The edges 21, 50 22, 23 are not sharp—they are rounded-off. The edge 22 of each wing projects farthest from the edges 18. The shields 3, 4 are close to the disk 5 and are made thin along the edges 18. 55

The device is used as follows: The device is brought below the hide of the killed animal and the disk 5 is set in motion. The edges 21, 22, 23 sever the hide. The device works in any position and may be handled 60 without any risk of making cuts in the hide or skin as the wings work in the manner of wedges. The hide may be severed quite clean and uninjured even by careless and inexperienced persons. 65

What I claim and wish to secure by Letters Patent is:

In a device of the character described the combination of a frame having two shields, a disk rotatably secured between both 70 shields, wings on said disk projecting over the outer edge of said shields, a group of semi-circular grounded beating edges on the outer ends of each of said wings, the central edge of said group of each group of said 75 beating edges protruding farther over the edges of said shields than that of the other two, a casing, and a spindle horizontally disposed in said frame carrying said disk, substantially as described and for the purpose set forth. 80

In testimony whereof, I affix my signature in the presence of two witnesses.

WILLY PFEFFERKORN.

Witnesses:

FRITZ QLE,
ARLON T. ADAMS.
